UNITED STATES PATENT OFFICE.

MYRON J. GLAUBER, OF BEVERLY HILLS, CALIFORNIA, ASSIGNOR TO BUCKNELL SUPPLY COMPANY, OF LOS ANGELES, CALIFORNIA, A CORPORATION OF CALIFORNIA, DOING BUSINESS AS SPHINX MANUFACTURING COMPANY.

COMBINED SPOUT AND SPRAY FIXTURE.

Application filed May 17, 1927. Serial No. 192,099.

This invention relates to combined spout and spray fixtures, and is more particularly related to a fixture including a single valve for controlling the mixing of hot and cold water and for delivering the same to either a spout mounted within a bathtub or the like, below the fixture, and to a shower or spray head mounted above the fixture.

In my co-pending application for combination spout and spray fixture, filed June 23, 1926, Serial No. 117,951, I have shown and described a combination spout and spray fixture, including an ejector device and a pair of valves for controlling the admission of hot and cold water to the ejector device, the ejector device being connected with a bathtub spout and with a shower head in such a manner that, when the hot and cold water are admitted to the ejector device, the mixed water is prevented from backing up into the shower head by the ejector device.

An object of this invention is to provide an improved form of fixture of the same type which includes only a single valve for controlling the hot and cold water and the mixing thereof.

Another object of this invention is to provide a combined spout and spray fixture including a single casting adapted to be connected at the opposed branches to hot and cold water supply pipes, and also providing a mixing chamber and an ejector device communicating with the mixing chamber, the single casting being connected at a second pair of opposed branches with a shower head above the casting and a spout mounted below the casting, and having a diverting valve mounted therein.

Another object of this invention is to provide a combined spout and spray fixture which includes only a single valve for the control of the mixing of hot and cold water to enable a reduction of the cost of installation of such a fixture, and which also may be installed with a minimum of labor and is comparatively inexpensive in maintenance and upkeep.

Other objects of this invention it is believed will be apparent from the following detailed description of a preferred embodiment thereof as illustrated in the accompanying drawings.

In the drawings:

Figure 1 is a side elevation of an installation embodying this invention illustrating

the same as mounted in position relative to a wall shown in section.

Figure 2 is a perspective sectional view of the mixing valve, ejector device and device providing the hot and cold water mixing chamber as embodied in this invention.

Figure 3 is a front elevation of the valve control handle and indicating dial escutcheon embodied in this invention.

Figure 4 is an enlarged fragmental sectional view of the spout embodied in this invention illustrating one form of diverting valve mounted therein.

In the preferred embodiment of this invention shown in the accompanying drawings, 1 illustrates a spray or shower head and 2 a spout. The spout 2 is illustrated as mounted in position to discharge water into a bathtub 3. Means are provided for mixing the hot and cold water and for controlling the flow of hot and cold water to the shower head 1 on the one end and the spout 2 on the other end, which means are preferably of the following construction: A mixing valve is provided which includes a body 4 having opposed branches 5 and 6. The branch 6, is adapted to be connected with the cold water supply pipe, and the opposed branch 5 is adapted to be connected with a hot water supply pipe. The body 4 is provided with a substantially cylindrical portion 7 which extends across the branches 5 and 6 and is provided with staggered ports 8 and 9 through which hot and cold water is admitted into the interior of the cylindrical portion 7 of the body 4. Mounted within the cylindrical portion 7 of the body 4 is a tight-fitting plug 10 which is provided with a cut away portion as illustrated at 11. The plug 10 is secured by any suitable means, as illustrated at 12, to the valve stem 13. The valve stem 13 is provided with compression threads 14 in any suitable or desired manner, as is well understood in the art, by means of which the stem 13 is adapted to be screw-threaded into the transverse branch 15 of the body 4. The connecting member 12 between the ground plug 10 and stem 11 provides a packing head which is adapted to seat upon the packing seat 16 when the plug 10 is rotated by means of the stem 13 to the position to shut off the cold water admitted to the branch 6, and the packing means provided by the connecting member 12 engaging the seat 16 shuts off the

supply of cold water which would otherwise flow through the port 9 from the branch 6. The particular form of mixing valve disclosed herein is not essential to the successful 5 performance of this invention, but it is believed that any suitable or desirable form of mixing valve might be employed with substantially equal results. The particular form of mixing valve disclosed herewith is fully 10 described and claimed in the co-pending application of Theodore T. Lederer, filed Nov. 13, 1926, Serial No. 148,176.

Screw-threaded as indicated at 17 to the branch 15 is an extension cap 18. The cap 18 15 is provided with a packing recess 19 within which a packing cone 20 is mounted. Additional packing means may be provided such, for example, as a lead washer 21, which is mounted at the inner end of the packing cone 20 in position to engage the end face of the branch 15. In order to properly guide the 20 stem 13 a pair of washers 22 are provided which are mounted within an annular recess formed in the branch 15, and closely fit the 25 stem 13.

In order to adapt the fixture to be easily mounted behind a wall 23 without regard to the position of the hot and cold water supply pipes, the caps 18 is provided for a considerable 30 portion of its length with threads 23 into which a threaded nipple 24 is screw-threaded. The threaded nipple 24 is provided at its outer end with an escutcheon holder 25 by means of which the escutcheon 26 is held in 35 position.

Preferably formed integral with the body 4 in front of the branches 5 and 6 are a pair 40 of transversely extending branches 27 and 28. The branch 27 is adapted to be connected by any suitable or desirable means as indicated at 29, with the bathtub spout 2. The branch 28 is adapted to be connected by any suitable 45 or desirable means such as indicated at 30 with the shower head or spray 1. Intermediate with the branches 27 and 28 there is provided within the casting a mixing chamber 31 within which the hot and cold water admitted thereto and controlled by the mixing valve is mixed prior to the same being discharged to either the spray 1 or the spout 2. Formed around the chamber 31 within the casting is a port 32 by means of which communication is maintained between the branches 27 and 28.

50 Means are provided for normally preventing the passage of water from the mixing chamber 31 through the port 32 and out the branch 28, which means preferably comprise a short section of tube 33 which is screw-threaded within the casting in communication at its inner end with the chamber 31 and extending into the branch 27 of the casting beyond the end 34 of the passage 32. The tube 33 being projected to slightly beyond 55 the entrance end 34 of the passage 32 provides

an ejector device which creates a suction within the passage 32 preventing the water from backing up through the passage 32, and hence from passing through the connecting means 30 and out of the spray 1 when it is desired to 70 discharge the water into the bathtub 3 through a spout 2. The use of this ejector device prevents all leakage of water from the spray or shower head 1 when it is not desired to employ the same for a shower. 75

In order to permit the hot and cold water mixed in the chamber 31 to be discharged through the spray 1 when desired, there is provided in the spout 2 diverting means 35 by means of which the water mixed within 80 the mixing chamber 31 is prevented from discharging from the spout 2 and is hence caused to back up around the ejector device and flow through the passage 32, connecting means 30 and, hence from the spray or shower 85 head 1.

The diverting means 35 may be of any suitable or desirable form, and are merely illustrated as comprising a disk 36 which is pivotally mounted within the spout 2 on a pin 90 37, to which an operating handle 38 is secured. The disk 36 is formed to closely fit within the passage formed through the spout 2, but it is not necessary to provide at this point a leak proof valve, as a slight leakage of water 95 through the spout 2 when the shower head 1 is being used is not noticeable as the water from the shower head 1, in the common installation, is discharging into the bathtub 3.

Means are provided for indicating the mixture of water being obtained within the mixing chamber 31 through the mixing valve, which means are preferably of the following construction: The escutcheon 26 which is held in position by means of the escutcheon holder 100 25 on the outer face of the wall 23, is provided around its periphery with indicating marks or words such as illustrated at 39. The handle 40 which is secured to the stem 13 of the mixing valve is provided with an indicating 105 arrow 41, and by means of the indicating arrow 41 and words 39 the user is enabled to set the handle 40 to give him approximately the desired temperature of his shower or bath. 110

Having fully described the preferred embodiment of my invention, it is to be understood that I do not wish to be limited to the details herein set forth, and my invention is 115 of the scope of the appended claims.

I claim:

1. In a device of the class described, the combination of a body having a pair of inlet branches and a pair of outlet branches, a mixing valve for controlling the inlet branches, 120 an ejector device formed within the body and connecting with a mixing chamber formed within the body, a spray head connected with one of the outlet branches, a spout connected with the other outlet branch, and a diverting 125 130

- valve operatively connected with the spout below the ejector device.
2. In a device of the class described, the combination of a spray head, a spout, hot and cold water supply pipes, a mixing valve connected with the hot and cold water supply pipes, an ejector device operably connected with the mixing valve outlet, means connecting the mixing valve outlet with the spray head, means connecting the mixing valve outlet with the spout, and a diverter valve operable in opened position to permit water to pass through said spout and in closed position to cause said water to pass through said head.
3. In a device of the class described, the combination of a mixing valve, hot and cold water supply pipes connected with the mixing valve, an ejector device operably connect-
- ed with the outlet of said mixing valve, a spray head, means connecting the spray head in position above and with the mixing valves, a spout, means connecting the spout with the mixing valve, and a diverter valve operably connected with said spout.
4. In a device of the class described, the combination of a mixing valve having hot and cold water inlets, an ejector device operably connected with said mixing valve, the mixing valve having an outlet communicating with a spray head, and an outlet communicating with a spout, and a diverting valve to transfer the flow of water either through the spout or through the spray head.

Signed at Chicago, Illinois, this fourteenth day of May, 1927.

MYRON J. GLAUBER.
